TRAVELING BAG

Martin L. Lee, Brooklyn, N. Y., and Ary Kaufmann, South Orange, N. J., assignors to K. Kaufmann & Co., Inc., Newark, N. J., a corporation of New Jersey

Application August 9, 1934, Serial No. 739,084

12 Claims. (Cl. 190—41)

This invention relates to improvements in traveling bags; and the invention has reference, more particularly, to a novel form and construction of frameless bag adapted to open at the bottom and sides, being separably closed at such points by a continuous slide fastener means, and having an integral intermediate top section between its side portions, with relation to which the latter swing to open or closed positions, and to the exterior of which top section a single carrying handle is attached.

This invention has for one object to provide a light weight frameless traveling bag of the novel form above mentioned.

Another object of the invention is to provide a novel traveling bag of the kind mentioned which is adapted to open out in flat lying position with its unitary side and intermediate top sections substantially disposed in a single plane; means being provided within the bag interior adjacent to the free end of one side section for removably affixing thereto garment supporting means, whereby the supported garments may be laid within and across said side and top sections; and additional means being provided for removable attachment transversely of the bag interior and adjacent to the top section so as to lie intermediate the side sections, over which the suspended garments may fold when the side sections are swung to and secured in closed together condition, and so that folded garments will be suspended, when the bag is closed, with the fold thereof adjacent to the top section and oppositely extending lengths of said garments disposed to respectively lie contiguous to the inner faces of the respective side sections; all to the end that the garments may be compactly and smoothly disposed within the bag and carried therein without risk of wrinkling or like distortion or massing.

Another object of the invention is to provide a pocket or compartment for carrying miscellaneous articles of clothing, toilet articles, etc., adapted to be suspended directly from or from points adjacent to the garment folding means, so as to lie between the lengths of the folded garments when the bag is closed.

Other objects of this invention, not at this time more particularly referred to, will be understood from the following detailed description of the same.

Illustrative embodiments of this invention are shown in the accompanying drawings, in which:—

Fig. 1 is a perspective view of the novel travel-

ing bag according to this invention, this view showing the same in its closed condition; Fig. 2 is a top end view of the same; Fig. 3 is a bottom end view of the same.

Fig. 4 is a plan view of the novel traveling bag in open condition, and as equipped with supporting means for carrying men's suits, the folding bar with miscellaneous article holding pocket connected therewith, being shown as about to be mounted in operative relation to the bag interior and to the suit disposed therein; Fig. 5 is a longitudinal vertical section through the open bag, with the folding bar and article holding pocket in place; and Fig. 6 is a longitudinal vertical section through the bag as closed for carrying.

Fig. 7 is a fragmentary plan view of the bag in open condition, and as equipped with supporting means especially adapted for women's gowns and dresses; and Fig. 7A is a fragmentary sectional view, taken on line 7A—7A in Fig. 7.

Fig. 8 is a vertical section of a modified form of the novel bag adapted for general use, the same being shown in closed condition.

Similar characters of reference are employed in the above-described views, to indicate corresponding parts.

Referring to said drawings, the novel bag according to this invention comprises a main body consisting of three sections, which, for convenience of description, will be referred to viz., as the upper side section 10, the intermediate or top section 11, and the lower side section 12. Preferably these sections are formed from a unitary or continuous sheet or piece of material, such as real or artificial leather, cloth or like suitable material. The intermediate or top section 11 is provided or faced at its interior surface with a stiffening strip 13 of any suitable comparatively rigid material, which extends contiguous thereto and transversely of the main body as a whole. In like manner, the side sections 10 and 12 are also preferably provided or faced at their interior surfaces, and adjacent and parallel to their free transverse marginal portions, with like stiffening or reenforcing strips 14. Otherwise the main body, thus constituted is preferably left more or less flexible or pliable; although it must be understood that the several sections may be stiffened throughout their entire area, if desired, so long as flexing portions adjoin the side sections respectively to the top or intermediate section. Preferably the main body is faced on its interior side with a lining 15, of any desired suitable material. Connected with the periphery of

the upper side section 10, to extend laterally inward and more or less at right angles to the plane of said side section, is a marginal member or gusset 16. This marginal member or gusset, in 5 the form of the novel bag shown in Figs. 1 to 6 inclusive, is preferably comprised of single continuous piece extending from a point at one end of the top or intermediate section 11 along one side edge of the side section 10, thence along the 10 free or outer end edge thereof, and then back along the opposite side edge thereof, back to a point at the opposite end of said top or intermediate section. That portion of the marginal member or gusset 16 bordering the free end edge 15 of the side section 10 is of uniform and maximum width, while the respective portions bordering the side edges of the side section 10 are each of diminishing width tapering toward the intermediate or top section 11. Connected with the 20 free periphery of the inner side section 12, and arranged and shaped in like manner, is a similar marginal member or gusset 17. Owing to the described shape of said members or gussets 16 and 17, the bag when closed will assume an 25 upwardly tapered form, as shown more especially in Figs. 1 and 6, whereby the bag, when closed will be somewhat wider at its bottom end than at its top end, thus providing room for the expansion of an article carrying pocket or receptacle 30 with which the interior of the bag may be provided, as will subsequently more fully appear.

The respective marginal members or gussets 16 and 17 are respectively provided at their opposite ends, with free terminal portions 18 and 35 19, which are inwardly turned over the adjacent end portions of the intermediate or top section 11, so that the terminal portions 18 converge upon the terminal portions 19, and so that their extremities may be suitably secured or anchored 40 to said intermediate or top section.

The peripheral margins of the main body composed of the side and top sections, together with the adjoined portions of the lining 15 and marginal members or gussets 16 and 17 are enclosed 45 in a binding member 20, all said parts together with said binding member being suitably secured together, as by stitching 21.

Secured to and extending around the free edge 50 portions of the respective marginal members or gussets 16 and 17 are tapes 22 provided with well-known slide fastener elements which, when operated by movement of the slider 23 thereover, are adapted to engage or disengage so as to secure or release the side sections of the bag for closing 55 or opening the latter. Pivotaly connected with the draw link 24 of the slider 23 is a slotted hasp member 25, which, when the slider is disposed at the end of its fastener element engaging stroke or movement serving to close the bag, may be 60 turned and engaged over a staple eye 26 fixed on the exterior side of the intermediate or top section, so that a pad-lock (not shown) may be applied to the staple against disengagement of said hasp member therefrom, thus locking the 65 slider against unauthorized bag opening manipulation after the bag is closed.

When the novel bag is equipped to carry garments in supported and folded condition therein, a garment supporting and suspending means is 70 provided in the free end of the upper side section 10. As provided for supporting men's suit, the garment suspending means comprises, for example, a post 27, the base 28 of which is centrally secured to the inner side of said side section 10 75 adjacent to its free end and at the portion there-

of which is stiffened by the reinforcing strip 14. Detachably mountable upon the post 27 is any suitable form of coat hanger device 29, which is preferably provided with a bottom bar 30 over which trousers may be folded so as to depend therefrom. At the end of the post 27 is an upstanding keeper lug 31, and secured to the hanger device is a suspension link 32 having a T-slot to engage over the post 27. Pivoted to the hanger device is a lock arm 33 having an angular extremity 34 which, when the link 32 is engaged on the post 27, may be turned to extend behind the keeper lug 31, thus preventing accidental disengagement of the hanger device from its supported relation to said post. If desired, said lock-arm 15 33 may terminate, at the end thereof extending oppositely from its pivoted connection to the hanger device, in a hook element 35. This hook element 35 may be upturned, when the hanger device is removed from the post 27, so as to serve 20 as a means for suspending the hanger device and garments carried thereby from a closet hook or the like.

When the bag is opened out to flat lying position, as shown in Fig. 4, a man's suit may be 25 mounted upon the hanger device 29, and thereupon the latter in turn mounted on the post 27 in suspended relation thereto. When this is done, the suit will extend in smooth supported position along and contiguous to the interior 30 surfaces of the flat lying side and top sections of the main body. Preparatory to closing the side sections together, after the garments are disposed in the bag as described, a detachable folding means is secured over the garments adjacent to 35 the top section 11 and intermediate the side sections 10 and 12 as extending from the latter. This folding means and the means for detachably supporting the same in place, comprises, for example, yieldable perforate bracket tongues 36, the bases 40 of which are respectively secured adjacent to the ends of said top section 11 as reinforced by the stiffening strip 13. The free end portions of these bracket tongues 36 are outwardly flared and are provided with descending guide grooves or 45 channels 38 leading to the perforations of the bracket tongues. A folding bar 39 of suitable length to lie between said bracket tongues is provided. Suitably affixed to and projecting from the ends of said folding bar 39 are coupling studs 50 40. To mount the folding bar in operative position it is aligned between the bracket tongues 36 with the coupling studs 40 thereof engaged in the guide grooves or channels 38, so that by pressing inwardly upon the folding bar, the studs 40 will be 55 carried into position opposite perforations of the bracket tongues, so that the latter will snap over said studs, thus locking the folding bar in place.

When the folding bar is in place, the side sections 10 and 12 may be swung relative to the top 60 section 11, and thus to closed relation, thereby folding the garments intermediately over the folding bar (see Fig. 6). The slide fastener means may now be manipulated to secure the side sections in closed together relation. Centrally secured to the exterior side of the top section 11 is a carrying handle 41. When the bag is closed, the side sections 10—12 will depend from the top section 11, and when the bag is picked up by the carrying handle, the folding bar 39 will be disposed adjacent to the top end of the bag interior, thus allowing the folds of the contained suit to hang smoothly, and unsubjected to wrinkling or shifting movement, from the folding bar and respectively contiguous to the opposite side 75

sections of the closed bag, as will be evident from an inspection of Fig. 6.

When the bag is opened with the side and top sections lying in a common plane, the same may be hung up in a closet or against a wall without removing the outer garments therefrom, thus exposing the same to air until their use is desired. To this end an external suspension loop or ring L is centrally secured to the end periphery of the upper side section 10, as shown in the drawings.

When utilizing the novel bag structure for carrying women's gowns in smoothly supported and packed condition, some modification of the garment supporting or suspending means is desirable. In Fig. 7 an illustrative arrangement of such supporting and suspending means especially adapted for women's gowns and dresses is shown. In this arrangement the garment supporting means comprises a pair of laterally spaced apart notched brackets 42, having pivoted releasable keeper arms 43. The bases 44 of said brackets are secured to the inner side of said upper side section 10 adjacent to its free end, and at the portion thereof which is stiffened by the reinforcing strip 14. Removably mountable on and to extend between said bracket 42 are one or more dress hanger rods 45 having coupling studs 46 projecting from their ends to engage notches of said brackets. The dresses are folded over the rods so as to depend therefrom in smoothly extending relation to and contiguous to the interior surfaces of the main body. The folding bar 38 is utilized to hold the central portions of the thus suspended dresses to fold the same, when the side sections of the main body are closed together, much in the manner and with the same general effects already described.

In order to afford provision for carrying in the bag other articles of clothing and miscellaneous articles, in addition to the suspended and folded outer garments above mentioned, a pouch-like receptacle or pocket 47 of suitable shape is provided. Preferably this receptacle or pocket 47 is furnished with a cover flap 48 for closing the same. Any suitable means may be provided for detachably suspending the receptacle or pocket 47 from a point adjacent to the top section 11, so that the same is disposed between the depending folds of the suspended and folded outer garments. The most convenient and consequently the preferable manner of suspending the receptacle or pocket 47 in such disposition is to provide the same with a transverse loop 49 through which the folding bar 38 is engaged, whereby, when said folding bar is operatively mounted and secured in place within the bag, the receptacle or pocket 47 will depend therefrom, as shown more especially in Figs. 5 and 6 of the drawings.

The novel bag structure per se may be utilized without outer garment supporting and folding means, and consequently as portable carrier for general use, thus providing in connection with such use the advantages incident to its frameless structure, light weight and novel bottom opening form whereby it may be laid out flat when open. In such case, the external shape of the bag may be modified from the above-described upwardly tapered form to a more or less rectangular form if desired. The bag structure thus modified is shown in Fig. 8, wherein the corresponding elements of the exterior structure are identified by the same reference characters above described. Within the interior of this arrangement of the bag, each side section provided with any suit-

able means to form compartments in connection therewith, as e. g. the partitions 58.

We are aware that many changes could be made in the above described constructions, and that apparently widely different embodiments of this invention could be made without departing from the scope thereof; consequently it is intended that all matter contained in the above description or shown in the accompanying drawings shall be interpreted as illustrative and not in a limiting sense.

We claim:—

1. A traveling bag, comprising a unitary main body consisting of hingedly interjoined side and top sections adapted when the bag is opened to extend in a common plane, but wherein said side sections are folded relative to said top section and toward one another to close the bag, said side sections having marginal portions to form bottom and end walls of the bag when closed, said marginal portions having releasable cooperable means to fasten the bag closed, garment supporting means, means within and adjacent to the free end of one side section for detachably mounting said garment supporting means whereby garments suspended therefrom will extend along and contiguous to the interior surfaces of said side and top sections, a detachable folding means adapted to be mounted across the portions of the suspended garments contiguous to said top section and over which the garments will fold so as to depend therefrom when the side sections are turned to bag closing relation, and retaining means affixed to said top section to receive and support said folding means.

2. A traveling bag, comprising a unitary main body consisting of hingedly interjoined side and top sections adapted when the bag is opened to extend in a common plane, but wherein said side sections are foldable relative to said top section and toward one another to close the bag, said side sections having marginal portions to form bottom and end walls of the bag when closed, said marginal portions having releasable cooperable means to fasten the bag closed, garment supporting means, means within and adjacent to the free end of one side section for detachably mounting said garment supporting means whereby garments suspended therefrom will extend along and contiguous to the interior surfaces of said side and top sections, a detachable folding means adapted to be mounted across the portions of the suspended garments contiguous to said top section and over which the garments will fold so as to depend therefrom when the side sections are turned to bag closing relation, retaining means affixed to said top section to receive said folding means and an auxiliary receptacle for disposition between the depending portions of the suspended and folded garments within the bag interior.

3. A traveling bag, comprising a unitary main body consisting of hingedly interjoined side and top sections adapted when the bag is opened to extend in a common plane, but wherein said side sections are foldable downwardly relative to said top section and toward one another to close the bag, said side sections having marginal portions to form bottom and end walls of the bag when closed, slide fastener means for joining the free meeting edges of said marginal members in secured closed together condition when said side sections are in closed relation, garment supporting means, means within and adjacent to the free end of one side section for detachably mounting said garment supporting means whereby gar-

ments supported therefrom will extend along and contiguous to the interior surfaces of said side and top sections, a removable folding bar, means at the inner side of said top section for detachably and adjustably securing said folding bar by its ends across the suspended garments to fold the latter along a line parallel and adjacent to the inner side of said top section and so that opposite end portions of the garments will depend from said bar when said side sections are turned to bag closing relation, and a carrying handle centrally mounted on the exterior face of said top section.

4. A traveling bag, comprising a unitary main body consisting of hingedly interjoined side and top sections adapted when the bag is opened to extend in a common plane, but wherein said side sections are foldable downwardly relative to said top section and toward one another to close the bag, said side sections having marginal portions to form bottom and end walls of the bag when closed, slide fastener means for joining the free meeting edges of said marginal members in secured closed together condition when said side sections are in closed relation, garment supporting means, means within and adjacent to the free end of one side section for detachably mounting said garment supporting means whereby garments supported therefrom will extend along and contiguous to the interior surfaces of said side and top sections, a removable folding bar, means at the inner side of said top section for detachably and adjustably securing said folding bar by its ends across the suspended garments to fold the latter along a line parallel and adjacent to the inner side of said top section and so that opposite end portions of the garments will depend from said bar when said side sections are turned to bag closing relation, a carrying handle centrally mounted on the exterior face of said top section, and an auxiliary receptacle for disposition between the depending portions of the suspended and folded garments within the bag interior.

5. A traveling bag, comprising a unitary main body consisting of hingedly interjoined side and top sections adapted when the bag is opened to extend in a common plane, but wherein said side sections are foldable downwardly relative to said top section and toward one another to close the bag, said side sections having marginal portions to form bottom and end walls of the bag when closed, slide fastener means for joining the free meeting edges of said marginal members in secured closed together condition when said side sections are in closed relation, garment supporting means, means within and adjacent to the free end of one side section for detachably mounting said garment supporting means whereby garments supported therefrom will extend along and contiguous to the interior surfaces of said side and top sections, a removable folding bar, means at the inner side of said top section for detachably securing said folding bar across the suspended garments to fold the latter along a line parallel and adjacent to the inner side of said top section and so that opposite end portions of the garments will depend from said bar when said side sections are turned to bag closing relation, a carrying handle centrally mounted on the exterior face of said top section, an auxiliary receptacle, and means to suspend said receptacle from said folding bar.

6. In a traveling bag, a stiffened top section and side members extending oppositely from the

lateral margins thereof and being downwardly foldable relative thereto into closed together relation, slide fastener means for joining the opposed marginal portions of said side members in closed together relation, garment supporting means transversely disposed within one side member adjacent to its free end, a demountable garment folding bar adjacent to the interior side of said top section and intermediate said side members, and retaining means affixed to said top section to receive and support said folding bar.

7. In a traveling bag, a stiffened top section and side members extending oppositely from lateral margins thereof and being downwardly foldable relative thereto into closed together relation, slide fastener means for joining the opposed marginal portions of said side members in closed together relation, garment hanger means demountably supported within one side member adjacent to its free end, a demountable garment folding bar adjacent to the interior side of said top section and intermediate said side members, and retaining means affixed to said top section to receive and support said folding bar, and a carrying handle centrally mounted on the exterior face of said top section.

8. In a traveling bag, a stiffened top section and side members extending oppositely from lateral margins thereof and being downwardly foldable relative thereto into closed together relation, slide fastener means for joining the opposed marginal portions of said side members in closed together relation, garment hanger means demountably supported within one side member adjacent to its free end, a demountable garment folding bar adjacent to the interior side of said top section and intermediate said side members, and retaining means affixed to said top section to receive and support said folding bar, a carrying handle centrally mounted on the exterior face of said top section, an auxiliary receptacle, and means to suspend said receptacle from said demountable folding bar whereby the same is removable from the bag therewith.

9. A traveling bag, comprising a main body arranged to fold along a medial line to form closed together side members capable of being opened out into a common flat plane, a garment hanger means demountably supported with one side member adjacent to its free end, a garment folding and supporting means movably related to said main body in adjusted spaced relation to the interior side of the medial line of fold thereof, and means to hold said side members in closed together relation.

10. A traveling bag, comprising a main body arranged to fold along a medial line to form closed together side members capable of being opened out into a common flat plane, a garment hanger demountably supported within one side member adjacent to its free end, a garment folding means, means to detachably support said folding means in opposed and adjusted spaced relation to the interior side of the medial fold of said main body, whereby garment portions folded thereby are clamped between said medial fold of said main body and said folding means, means to engage said side members in closed together relation, and a carrying handle secured to the exterior side of the medial fold of said main body.

11. In a traveling bag, a main body arranged to fold along a medial portion to form closed together side members capable of being opened out

into a substantially flat common plane, a garment folding and supporting means movably related to said main body in adjusted spaced and opposed relation to the interior side of the medial portion thereof, and means to hold said side members in closed together relation.

12. In a traveling bag, a main body arranged to fold along a medial portion to form closed together side members capable of being opened out

into a substantially flat common plane, a detachable garment folding and supporting rod, means to attach said rod in spaced opposed relation to the interior side of the medial portion of said main body, and slide fastener means for joining the free marginal portions of the main body side members in secured closed together relation.

MARTIN L. LEE.
ARY KAUFMANN.
